UNITED STATES PATENT OFFICE.

MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

HANDLE FOR ELECTRIC SNAP-SWITCHES.

SPECIFICATION forming part of Letters Patent No. 745,011, dated November 24, 1903.

Application filed September 23, 1903. Serial No. 174,283. (No model.)

To all whom it may concern:

Be it known that I, MONROE GUETT, a citizen of the United States, residing at Hartford, in the county of Hartford and State of Connecticut, have invented certain new and useful Improvements in Handles for Electric Snap-Switches, of which the following is a specification.

This invention relates to a handle which has a yielding stem for attachment to the spindle.

The object of this invention is to provide a handle consisting of parts that are simple to construct and easy to assemble and which will connect the handle firmly to the spindle with the necessary elasticity for properly holding the switch cover or plate in position.

This invention resides in a handle of insulating material having a yoke so embedded within it that the inner edges of the legs of the yoke extend into the socket and receive the notched head of the stem and the plate which holds the spring under tension upon the stem.

Figure 1 of the accompanying drawings shows a vertical transverse section of the handle. Fig. 2 shows a vertical longitudinal section of the handle. Fig. 3 shows a horizontal section, looking downwardly, on the plane indicated by the dotted line 3 3 of Fig. 2. Fig. 4 shows a view of the handle looking upwardly from the bottom, and Fig. 5 shows a plan of the plate.

The handle 1 may be formed to the desired shape of any suitable insulating material, preferably a molded composition. A yoke 2 is so embedded within the insulating material of the handle that the inner edges of its legs extend into the socket. It is preferred to stamp this yoke from thin metal with perforations, so that the insulation when molded will flow through the openings and hold the yoke firmly in place. Notches 3 are made in the inner edges near the ends of the legs of the yoke.

The stem 4, which is threaded to receive the ordinary switch-spindle, has a head 5, which fits the socket in the insulating material. Notches are cut in the edges of the head, so as to receive the inner edges of the

legs of the yoke when the stem is thrust into the socket. The walls of these notches engage with the edges of the yoke, so that the stem, while free to move longitudinally, will rotate with the handle. The spring 6 is placed upon the stem, and then the plate 7 is thrust upon the stem, so as to hold the spring compressed between the head of the stem and the plate.

The plate is shaped to fit the socket and has notches 8, which receive the inner edges of the legs of the yoke and allow the plate to be pushed into the socket as far as the notches in the yoke. After the plate has been pushed on the stem as far as the notches in the yoke it is rotated so the edges of the plate will pass into the notches. It is preferred to stamp pockets 9 in the plate, so that when it is turned sidewise sufficiently the pockets will receive the outer walls of the notches in the legs of the yoke. When the plate is turned to this position, the spring thrusts it outwardly and holds it so that it will not get out of position. In order to remove the mechanism from the interior of the handle, the plate may be pressed inwardly slightly and turned until the notches are opposite the yoke-legs, and then the plate will slip off and allow the stem and spring to be removed.

The invention claimed is—

1. A handle for an electric snap-switch having a body of insulating material with a socket, a yoke with notches in its inner edges embedded within the insulating material and having its inner edges extending into the socket, a stem having a head that fits the socket and notches that fit the inner edges of the yoke, a spring on the stem, and a plate held in the notches in the inner edges of the yoke, substantially as specified.

2. A handle for an electric snap-switch having a body of insulating material with a socket, a yoke with notches in its inner edges embedded within the insulating material and having its inner edges extending into the socket, a stem having a head that fits the socket and notches that fit the inner edges of the yoke, a spring on the stem, and a plate held in the notches in the inner edges of the yoke and having notches in its edges that allow it when

turned to be removed from the notches in the yoke, substantially as specified.

3. A handle for an electric snap-switch having a body of insulating material with a socket, a yoke with notches in its inner edges embedded within the insulating material and having its inner edges extending into the socket, a stem having a head that fits the socket and notches that fit the inner edges of the yoke,

a spring on the stem, and a plate that fits ¹⁰ the socket and has notches that fit the edges of the yoke, and pockets that are adapted to receive the outer walls of the notches in the yoke, substantially as specified.

MONROE GUETT.
